Primary Examiner — Justin C Dodson*Assistant Examiner* — Sydney M Evans(74) *Attorney, Agent, or Firm* — Murray, Ziel & Johnston; Aaron Powell(57) **CLAIM**

The ornamental design for a plant cover, as shown and described.

DESCRIPTION

FIG. 1 is a top, front, right side perspective view of a plant cover, showing my new design;

FIG. 2 is a bottom, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion 9 in FIG. 1.

The evenly dashed broken lines illustrate portions of the plant cover and form no part of the claimed design. The unevenly dashed broken lines define the boundaries of enlarged views and form no part of the claimed design.
